UNITED STATES PATENT OFFICE.

ABRAHAM NILSEN HOVLAND, OF CHRISTIANIA, NORWAY.

ELECTRIC CONDENSER OR LEYDEN JAR.

1,139,976.

Specification of Letters Patent.

Patented May 18, 1915.

Application filed May 26, 1911. Serial No. 629,730.

To all whom it may concern:

Be it known that I, ABRAHAM NILSEN HOVLAND, a subject of the King of Norway, residing at Christiania, Norway, have invented certain new and useful Improvements in Electric Condensers or Leyden Jars; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Leyden jars and condensers now in use and employed at radio-telegraph stations and the like, occupy a rather large amount of space in relation to their capacity. The Leyden jars now commonly used are of a 20 cylindrical shape with or without a constricted neck. If more jars are to be coupled together to increase the capacity, it is necessary to place them either alongside or on top of each other and when coupled in series a smaller jar is also placed inside a larger one, but then, as is well known, the capacity becomes less.

The present invention relates to an improved construction of condensers, the same 30 being made more or less of the shape of a cone or a hemisphere or a part-spherical segment, with the result that condensers of the same shape and size can be placed one inside the other. These condensers may then in 35 known manner, be coupled in parallel or by groups in series, as desired.

To increase the distance at the edge between the two coatings the condensers may be provided with an outwardly projecting 40 flange, which may be of different shapes.

In electrolytic condensers, it has been proposed to employ a nested series of pairs of metallic dishes or cones, members of each pair of dishes being separated by a correspondingly shaped dish of insulating material for the purpose of preventing the electrolyte from short circuiting members of a pair should one of these become punctured. The present invention however relates to condensers of the type referred to in which the edges of the two metallic coatings are separated by the rim portion of the hollow insulating body which extends beyond such edges.

55 In order to enable the invention to be

readily understood, reference is made to the accompanying drawing, in which:

Figures 1, 3, 4, 6, 7, and 9, are sectional elevations illustrating some forms of condensers with a flange. Fig. 2 is a similar view of a number of condensers of the kind shown in Fig. 1, nested and connected in parallel, and Figs. 5 and 8 represent in section elevation two different forms of the improved condenser, without a flange.

In Fig. 1, the hollow insulating or dielectric body *a* has the form of an inverted truncated cone provided with inner and outer metallic coatings *c* and *d* respectively. The open end of the hollow body *a* is formed 70 with a reversely coned flange *b* and it will be apparent that the provision of this flange *b* increases the distance over the surfaces of the dielectric from the edge of the coating *c* to the edge of the coating *d*.

Fig. 2 shows a number of such condensers nested and connected in parallel. The inner coating *c* of the uppermost condenser and the outer coating *d* of the lowermost condenser are connected to the terminal bar *g*. 80 The nesting of the condensers places the outer and inner coatings of neighboring condensers in contact with one another and therefore connections are made between alternate pairs of contacting coatings and the bar *g* and between the remainder of the pairs of contacting coatings and the bar *h*.

In Fig. 3 the hollow body *a* is made very shallow and the flange is curved in cross section.

In Fig. 4 the edge of the reversely coned flange *b* is bent downwardly and inwardly.

The construction in Fig. 5 is similar to that in Fig. 1 only the flange is dispensed with.

Fig. 6 illustrates a hollow body having more or less the shape of a basin, the flange in this case being bent outwardly and downwardly.

The construction in Fig. 7 is similar to that in Fig. 3 only the body *a* is part-spherical instead of conoidal.

The construction in Fig. 8 is similar to that in Fig. 5 excepting that the bottom of the hollow body is concave instead of being flat.

Fig. 9 illustrates an inverted hollow body of conical cross section and formed with a curved flange outwardly and upwardly curved.

The condensers may of course, without departing from the above-mentioned fundamental shape be variously constructed and those shown in the drawing are only given as examples.

As a dielectric, insulating materials such as glass, china, flint, stoneware, ebonite, oil, paraffin, micanite, paper, and the like may be used.

For portable stations a substance that does not easily break on being violently shaken is preferably employed.

The metal coatings may be either caused to adhere directly to the insulating material or be made of somewhat thicker metal in the form of cups, hemispheres, part-spherical segments and so on, so that they may be readily placed in the vessels made of insulating material.

Fig. 2 illustrates only one of the ways in which the condensers may be assembled; this may be done in many different ways as they can be placed or arranged with their axes horizontal or vertical and either with the hollow bodies in the position shown in Fig. 2 or inverted as shown in Fig. 9.

Claims—

1. A Leyden-jar battery composed exclu-

sively of solid materials consisting of a number of contacting elements all of the same shape and size, each comprising a hollow dielectric rigid body provided with interior and exterior metal coatings, the interior coating of one element contacting with the exterior coating of the next element and the rims of said elements provided with an outwardly extending collar.

2. A Leyden-jar battery consisting of a number of contacting elements all of the same shape and size, each of said elements comprising a hollow di-electric body provided with interior and exterior metal coatings, the interior coating of one element contacting with the exterior coating of the adjacent element, said elements having outwardly and downwardly extending rims free from coating, and conductors to which the coatings between alternate elements are electrically connected.

In testimony that I claim the foregoing as my invention, I have signed my name in presence of two subscribing witnesses.

ABRAHAM NILSEN HOVLAND.
